UNITED STATES PATENT OFFICE.

WILLIAM BOSWELL, OF PONTIAC, MICHIGAN.

IMPROVEMENT IN MILK-RACKS.

Specification forming part of Letters Patent No. 118,098, dated August 15, 1871.

To all whom it may concern:

Be it known that I, WILLIAM BOSWELL, of Pontiac, in the county of Oakland and State of Michigan, have invented a new and useful Improvement in Milk-Racks; and I do declare that the following is a true and accurate description thereof, reference being had to the accompanying drawing and to the letters of reference marked thereon, and being a part of this specification, in which my invention is shown in perspective.

The nature of this invention relates to an improvement in milk-racks, whereby vermin are prevented from getting at the milk, and creeping insects attempting to reach it are caught and destroyed. This invention consists in incasing the bottom of the revolving standard, upon which the arms forming the milk-rack are fastened with a smooth metallic surface, high enough to prevent any vermin from gaining a foothold on the wooden part of the standard, and surmounting this metallic surface with an annular cup fitted close to the standard, which is to be filled with molasses or other sweet sticky substance or oil, and in placing a similar annular cup at the top of the standard for the same purpose, and in the safe placed beneath the last-mentioned cup and above the milk-rack, circular in form, and extending over the outer edges of the pans, so as to form a cover for the racks.

In the accompanying drawing, A represents the floor or other convenient platform, in which the revolving standard B is stepped. C is the metallic surface surrounding the bottom of the revolving standard B, and surmounted by the annular cup D closely fitted to the standard B, to contain oil or molasses to entrap and destroy any insects that may fall therein. E are the arms on the standard B forming the milk-rack, and F is the circular safe placed above the milk-rack and extending far enough from the standard B to cover the outer edges of the milk-pans placed on the racks E, whereby vermin are prevented from getting at the milk from the top; and G is an annular cup, similar to the cup D, and used for a like purpose; and H is the ceiling or other convenient beam, in which the revolving shaft B is journaled at the top, as and for the purposes above set forth.

What I claim as my invention, and desire to secure by Letters Patent, is—

The revolving standard B, the metallic surface C, the annular cups D G, the safe F, with the arms E, when combined to operate as and for the purposes substantially above set forth.

WILLIAM BOSWELL.
